UNITED STATES PATENT OFFICE.

ARTHUR ALBERT KIM, OF PITTSBURGH, PENNSYLVANIA.

GASOLINE RESERVE TANK.

Application filed September 10, 1923. Serial No. 662,024.

To all whom it may concern:

Be it known that I, ARTHUR ALBERT KIM, a citizen of the United States, residing at Pittsburgh, in the county of Allegheny and State of Pennsylvania, have invented new and useful Improvements in Gasoline Reserve Tanks, of which the following is a specification.

This invention relates to containers, and 10 more particularly to what I term a gasoline reserve tank.

One of the main objects of the invention is to provide a reserve tank which may be readily mounted in a gasoline tank of standard construction such as is ordinarily used on automobiles, this reserve tank also acting, as a baffle to prevent excessive splashing of the gasoline in the main tank. A further object is to provide a reserve tank 20 so constructed and arranged as to insure that it will be kept filled until such time as it is desired to use the reserve supply of gasoline. Further objects will appear from the detail description.

25 In the drawings:—

Figure 1 is a side view of the reserve tank as applied, partly in section;

30 Figure 2 is a transverse section through the main tank, showing the reserve tank as applied;

Figure 3 is a top plan view of the reserve tank;

35 Figure 4 is a section taken substantially on line 4—4 of Fig. 3;

Figure 5 is a view similar to Fig. 1 showing a modified form of filling tube;

Figure 6 is a longitudinal section through the filling tube illustrated in Fig. 5;

40 Figure 7 is a section taken substantially on line 7—7 of Fig. 6.

My reserve tank is intended to be used in connection with a tank A of known construction which is provided with a nipple or collar B to facilitate pouring of gasoline into the tank. Within the main tank A I mount a reserve tank 1 with the upper portion of which communicates one end of a filling tube 2 which is provided at its other end with a vertically extending arm 2^a which projects upwardly within the nipple or neck B. Tank 1 is truncated at its upper and lower portions to provide openings or spaces 3 and 4 at the upper and lower portions, respectively, of tank A, these spaces

establishing communication between the two portions of tank A at the opposite sides of the reserve tank 1. A pet-cock 5 is connected to tank 1 at the bottom thereof and is opened or closed, as desired, by means of a rod 6 which passes through a packing gland 7 on the top of tank A, this rod being preferably provided at its upper end with a head 8.

The top of reserve tank 1 is slightly dished transversely and is provided with a plurality of openings 9 which permit gasoline which is splashed upon the top of the tank to enter it thus insuring that the reserve tank will be maintained full or approximately full of gasoline. As will be noted more clearly from Figure 1, tank 1 tapers downwardly thus providing, at each side of the tank, an upwardly and outwardly inclined surface, the side walls of the tank acting as baffles to prevent excessive movement or splashing of the gasoline in tank A, the effectiveness of this baffle being materially increased by the upward and outward inclination of the side wall of the tank.

If preferred, tube 2 may be replaced by a tube 11 of telescoping construction, this tube consisting of an inner member 12 which communicates with tank 1 and an outer member 13 is slidable within the inner member. This outer member has its outer end cut away at its upper portion so that, when the tube is extended, gasoline poured into spout B will enter the outer member 13 and flow through tube 11 into reserve tank 1. When the reserve tank is full the overflow will, of course, flow into the main tank A. Preferably, though not necessarily, sections 12 and 13 of tube 11 are provided with ribs 14 and 15, respectively, which are in sliding engagement and act to prevent turning of section 13 relative to section 12 thus insuring that the cut-away upper portion of the outer end of outer section 13 will be positioned upwardly within the nipple or nozzle B. Also, outer section 13 is preferably provided, adjacent to its outer end, with an angularly directed finger 16 which serves to limit inward movement of section 13 and facilitates moving of this section into operative position.

What I claim is:—

In combination with a main tank, a sup-

plemental tank positioned within the main tank and having its top wall spaced away from the top of the main tank, the top wall of the supplemental tank being concaved and perforated to receive gasoline splashed thereon and direct it into the supplemental tank, means for filling the supplemental

tank, and means for discharging the contents of the supplemental tank into the main tank.

10

In testimony whereof I affix my signature.

ARTHUR ALBERT KIM.
